UNITED STATES PATENT OFFICE

2,510,626

PAPER FEED DEVICE FOR PRINTING
BUSINESS MACHINES

Charles W. Geisheck, Detroit, Mich., assignor to
Burroughs Adding Machine Company, Detroit,
Mich., a corporation of Michigan

Application August 20, 1947, Serial No. 769,641

4 Claims. (Cl. 197—133)

1

This invention relates to an improvement in paper-feed mechanism for business machines. It has to do particularly with mechanism for feeding long or so-called "continuous" paper strips which are commonly supplied in rolls which may consist of either one strip or a plurality of strips wound together in the same roll. Double wound roll paper is used, for example, when it is desired that the machine on which it is used shall produce a record on successive lengths of one paper strip which may be torn off or severed for presentation to customers or for other purposes, and a duplicate record shall be produced on a second strip which is to be preserved for the use of the proprietor.

When feeding either single or double paper strips around a rotatable platen roller, there is generally a tendency for the paper to skew so that, as the platen roller rotates, the paper strip "creeps" laterally on the platen which frequently results in the paper encountering portions of the machine at one side or the other of its intended path and becoming torn and sometimes becoming jammed and causing annoyance and loss of time to clear the mechanism of the torn and wrinkled paper. Also when two paper strips are drawn from a double wound single roll of paper and fed around a platen roller against which they are pressed by feed rollers, slack will accumulate in one of the strips between the point where it leaves the supply roll and the point where it is gripped between the platen and feed rollers and, if such slack is not removed at frequent intervals, the slack paper strip folds and wrinkles as it passes between the platen and feed rollers and often causes tearing and jamming of the paper in the mechanism. Such formation of slack in one of the strips of paper drawn from a double wound supply roll results principally from the fact that the outermost of the strips of the double wound supply roll is longer and unwinds faster than the inner one of the strips. The difference in the rates of unwinding of the outer and inner strips of double wound rolls increases as the diameter of the roll diminishes as the roll is used up. The accumulation of slack in one of the two strips may be influenced also by other factors which differ in different structures.

An object of the invention is to provide simple and inexpensive means to eliminate objectionable "creeping" of long or continuous paper strips lengthwise of the platen roller.

Another object of the invention is to provide simple and inexpensive means to eliminate objectionable accumulation of slack in paper strips drawn from double wound paper supply rolls.

2

Other objects and advantages of the invention will be apparent from the following description of a preferred embodiment of the invention shown in the accompanying drawings in which:

5 Fig. 1 is a perspective view of a paper handling structure of a calculating machine provided with the invention, certain parts of which, including a cover, are omitted;

Fig. 2 is a right side elevation of the structure 10 of Fig. 1;

Fig. 3 is a fore and aft vertical section taken in a plane at the right-hand end of the paper supply roll;

Fig. 4 is a detail; and

15 Fig. 5 is a perspective view similar to Fig. 1 but with the casing or closure members in place.

In the drawings, the invention is illustrated as applied to a well known Burroughs portable calculating machine generally like that disclosed 20 in Patent No. 1,853,050 to A. A. Horton. The machine chosen for purposes of illustration has a platen roller and paper feeding structure supported in a stationary frame or so-called stationary paper "carriage" on the upper rear portion 25 of the machine.

In the illustrated machine, the paper "carriage," which is equipped to handle double wound roll paper, comprises right and left vertical end plates, 10 and 11, each having front and rear 30 inwardly turned feet secured by headed screws and nuts or the like to a base plate 12 (Figs. 2 and 3) which in turn is secured as by screws or the like to the upper rear portion of the machine. The end plates 10 and 11 are further interconnected and braced by a transversely extending rear portion, of inverted V-section, of a paper 35 guide member 13 (Fig. 3), and tie rods, such as 14 and 15. The platen roller 16 is secured upon a shaft 17 journaled in the end plates 10 and 11.

40 The supply roll 18 of paper is rotatably supported on a rod 19 which is removably supported in upper rear extensions of the side plates 10 and 11. From the roll 18, the paper strips 20 and 21 are led over the guide 13 and under the platen roller 16 between the latter and forwardly extending portions 22 of the guide 13 curved to conform to the cylindrical form of the platen. The paper strips are led further around the platen roller and between the latter and a tear-off blade 45 23 which is suitably supported on the side plates 10 and 11.

50 A suitable ribbon mechanism which may be like that shown in the Horton Patents Nos. 1,853,050 and 1,690,487 supports a stretch of ink ribbon 24 between the paper strip 20 on the forward side of the platen and the type bars 26 to

ink the impressions which the latter produce on the paper. To color duplicate impressions on the paper strip 21, either the rear side of the strip 20 may be carbonized, or a strip of carbon paper may be wound between the strips 20 and 21, or a second stretch of ink ribbon 25 (Fig. 1) may be employed, in which latter case, a double ribbon mechanism such as shown in the Racz and Cannon Patent No. 1,997,077 may be provided in place of the ribbon mechanism shown in the Horton patents.

The paper webs 20 and 21 are normally held in feeding relation to the under side of the platen by pressure rolls 27 positioned between the guide extensions 22 and supported on shafts 28 which are supported at their ends in the forward and rearward ends of cradle arms 29 which are notched on the under edges of their middle portions to be rockably supported on the pressure roll supporting rod 30 in spaced annular grooves formed in the latter. The rod 30 passes through a generally rectangular aperture 31 in the front lower portion of the side plate 11 and is received in an inverted V-shaped notch 32 (Fig. 4) in the lower edge of the side plate 10. The right-hand end of the rod 30 is yieldingly held in the notch 32 by springs 33 and 34 connected at their lower ends to the right-hand end of the rod 30 and at their upper ends to studs secured in the side plate 10 forwardly and rearwardly, respectively, of the shaft 17. A spring (not shown) located on the left side of the side plate 11 similarly to the spring 33 urges the rod 30 forwardly and upwardly in the aperture 31. Under the tensions of these springs, the pressure rolls 27 yieldingly press the paper into feeding engagement with the platen roller.

Flat cuts are formed as at 35 (Fig. 4) in one side of the rod 30 in alignment with each of the plates 10 and 11 so that the rod 30 normally does not contact with the upper forward edges of the aperture 31 and notch 32 and thus prevent the pressure rolls 27 from pressing the paper against platen. The left end of the rod 30 is bent upwardly to form a finger lever 300 which the operator may rock forwardly when desired to cause the rear edges of the flats 35 on the rod 30 to cam the rod downwardly and rearwardly from the upper front edges of the aperture 31 and notch 32 to space the pressure rolls 27 away from the platen roller 16 when desired, for example, to facilitate threading of the paper webs from a new supply roll around the platen.

The usual platen twirler 36 is secured on the right-hand end of the shaft 17 for manually rotating the platen to manually feed the paper when desired. Automatic line-spacing feed of the paper during machine operation is effected by means of a line-spacing ratchet wheel 37 secured on the platen shaft 17 on the right-hand side of the side plate 10 and engageable by the forward end of a line-spacing pawl 38 (Fig. 1). The pawl 38 is pivoted at its rear end upon a stud 39 secured in a lever 40 pivoted on a stud 41 secured in and projected rightwardly from the right side plate 10. The pawl 38 is urged clockwise (Fig. 1) into engagement with the ratchet wheel 37 by a spring 42 connected between the pawl 38 and a stud secured in the rear end of a lever 43. The lever 43 is pivoted at its forward end on a stud 44 secured in the upper front corner of the side plate 10 and carries a roller stud 45 which the spring 42 urges against the teeth of the ratchet wheel 37 whereby the platen is yieldingly held against unintentional rotation. The lower end

5 of the lever 40 carries a roller stud 46 (Fig. 1) which is positioned in a notch in the upper end of the lever 430 (which corresponds to the lever 331 of the Horton Patent No. 1,853,050) which is rocked first rearwardly and then forwardly by power in each operation of the machine whereby the line space pawl 38 is drawn rearwardly in an idle movement, then returned forwardly in each operation of the machine to rotate the platen and advance the paper strips a line space in each machine operation.

10 It is normally intended that, after each transaction or group of entries is recorded upon a portion of the paper strip 20, such portion of the latter is to be torn off over the edge of the tear-off plate 23 either to be handed to the customer or utilized in some other desired manner. The duplicate strip 21, however, is intended to be preserved as a continuous complete record of the work performed on the machine. The strip 21 passes over a plate 47 which may serve as an autographic table and is pivotally supported by lugs 48 at its lower front side corners engaging in apertures in the side plates 10 and 11 to permit the plate 47 to be swung forwardly to facilitate insertion of a new paper supply. Rearward rocking of the table 47 is limited by engagement of rearwardly turned edge portions 49 thereof against the upper edges of the side plates 10 and 11. The table 47 may be latched in its normal rearward position by engagement of a stud 50 (Fig. 2) on the inner side of the rearwardly turned left-hand edge portion 49 thereof by a latch 51 operated and controlled by a key operated lock, indicated generally at 52, which will be referred to again hereinafter.

15 From the upper edge of the table 47, the paper web 21 passes rearwardly over a guide plate 53 the forward edge of which is mounted on the upper rear edge of table 47 by a hinge 54 (Fig. 2). Movement of the rear end of the plate 53 downward beyond its normal position is prevented by engagement of the plate against a lug 540 extending from the forward member of the hinge. 20 From the rear edge of the plate 53, the web 21 passes downwardly to a take-up roller 55 comprising a hollow cylindrical portion closed at its right-hand end and rotatably supported on a spring-pressed retractable stud 56 carried in the right-hand one of a pair of arms 57 extending rearwardly from a bracket 58 having forwardly bent portions secured on top of the rear feet of the end plates 10 and 11 by the screws or the like which secure those feet to the plate 12. The left-hand open end of the take-up roller 55 removably fits upon a keyed hub of a pulley and ratchet wheel assembly 62, 70 rotatably mounted on a stud carried in the left arm 57. Within the hollow cylindrical portion of the take-up roll 55 is loosely positioned a piece of relatively heavy tubing 59 (Fig. 3) which aids in frictionally securing the end of the tape 21 to the take-up roller 55 when the end of the tape is inserted through a slot 60 in the roller 55 at the time of starting a new supply of paper.

25 The take-up roller 55 is automatically driven in the paper winding direction by means of a coil-spring belt 61 passing around the pulley 62 (Figs. 2 and 3) secured on the left end of the take-up roll 55, said belt also passing around the left end of the platen roller 16 in a groove 63 cut therein. The belt is engaged by an idler pulley 64 rotatably supported on the rod 14 in an aperture in the paper guide 13 and is also engaged by an idler pulley 65 rotatably supported

on a stud carried by a lateral lug 66 bent upwardly from the left side of the bracket 58. The ratio of diameter of the platen 16 to the diameter of the bottom of the groove therein is less than the ratio of the diameter of the take-up roll 55 to the effective diameter of the pulley 62, so that, as the platen is rotated in the paper-feeding direction with the pressure rollers 27 pressing the papers into feeding relation to the platen, the tape 21 between the platen roller 16 and the take-up roller 55 is pulled taut, and the lower stretch of the coil-spring belt 61 between the take-up roller 55 and the platen 16 is tensioned. The friction characteristics of the belt 61 and pulley 62 and the initial tension of the belt are so chosen that the belt will slip around the pulley before the tension on the paper 21 becomes so great as to cause danger of breakage of the paper strip 21.

It will be apparent that after a certain amount of line space rotation of the platen, the portion of the tape 21 extending from the front feed roller 27 to the take-up roll 55 will be taut although, for reasons hereinbefore pointed out, that portion of the tape 21 extending from the supply roll 18 to the rear feed roll 27 would be slack as indicated by the dotted line 71 in Fig. 3 if no provisions were made to take up such slack. In accordance with the present invention, however, all slack in the tape 21 between the supply roll 18 and the rear feed roll 27 is automatically periodically taken up before it can accumulate to any amount sufficient to cause any difficulty. For this purpose a lever 72, pivotally supported on the stud 41, has its forward end 73 bent leftwardly and then rearwardly for engagement against the top of the right-hand end portion of the feed roll supporting rod 39. A lug 74 on the rear portion of the lever 72 is bent leftwardly behind the rear edge of the lever 40. The parts are so proportioned that when the lever 40 is swung rearwardly in each machine operation, the lever 72 is also rocked counterclockwise (Fig. 2) so that its forward end portion 73 depresses the right-hand end of the pressure roller supporting rod 38 downwardly against the tension of the right-hand springs 33 and 34 whereby the pressure rollers 27 are retracted from the platen sufficiently to permit the accumulated tension in the lower stretch of the coil spring belt 61 to slide the paper tape 21 around the platen to remove any slack existing in the tape 21 between the platen and the supply roll 18. As the lever 40 returns forwardly the right hand springs 33 and 34 return the pressure rolls 27 into engagement with the platen. The proportions of the ratchet 37 and pawl 38 and their movements are such that the rollers 27 again press the paper into feeding engagement with the platen before the line space movement of the platen by the forwardly moving pawl 38 commences. That is, the pawl 38, in the rearmost portion of its movement, moves substantially rearward of a tooth of the ratchet 37 without slipping past the next tooth so that in the first part of its forward movement, while the rolls 27 are returning to normal, the pawl 38 moves idly before effecting driving engagement with a tooth of the ratchet 37.

As the tape 21 is thus pulled around the platen 16 to take up any slack therein, it is also straightened in its path around the platen so that any "creeping" of the tape laterally of the platen which might result from extensive rotation of the platen with the pressure rolls 27 in feeding engagement therewith will be prevented.

To prevent unnecessary and undesirable unwinding of the supply roll 18 when the tape 21 is pulled around the platen by the belt 61, a frictional brake for the supply roll 18 is provided in the form of a plate 75 (Fig. 3) which is loosely supported on the rod 19 and provided with studs 78 and 79 projecting into bushings 76 and 77 secured on the inner side of the end plate 11. A coiled compression spring 80 surrounds the bushing 77 between the left face of the plate 75 and the right face of the plate 11 to press the plate 75 into frictional braking engagement with the left end face of the supply roll 18.

The tape 21 wound on the take-up roller 55 is protected against unintentional injury as well as unauthorized access by a cover member 81 (Fig. 5) pivotally mounted on rearwardly turned lateral portions 82 of the lower end of the bracket 58. The forward portion of the left-hand wall of the cover 81 carries the key operated lock 52 so that neither the table 47 nor the cover 81 may be moved from normal position except by the proprietor or other person having possession of the key for the lock 52.

Retrograde movement of the take-up roll 55 is prevented by a pawl 67 (Figs. 2 and 3) pivoted on a stud on the inner side of the left-hand arm 57 and urged clockwise by a spring 68 connected between the pawl 67 and a stud 69 secured in the bracket 58 whereby the rear end of the pawl 67 is yieldingly held in engagement with the ratchet wheel 70 at the left-hand end of the take-up roller 55. Also, reverse rotation of the platen which might tear the tape 21 is prevented by the pawl 38 and ratchet 37.

An auxiliary cover member 83 (Fig. 5) to enclose the portions of the line spacing mechanism located on the right-hand side of the plate 10, is secured to the right ends of the studs 41 and 44 as by headed screws passing through the cover member 83 and threaded into the ends of the studs 41 and 44.

It will be apparent to those skilled in the art that the invention may be applied to various forms of paper handling structure for various types of business machines. It may also be employed in paper handling mechanism used with various kinds or forms of multiple papers such, for example, as the so-called fan-folded or super-folded paper supplies. To those ends, the structure is susceptible of variation and modification within the scope of the appended claims.

I claim:

1. In a paper feeding mechanism for printing business machines having a rotatable platen roller around which a plurality of thicknesses of paper are passed, paper pressing means to press the papers into feeding relation to the platen roller, said pressing means being movably mounted for movement toward and away from the platen roller, yieldable means to urge the pressure means toward the platen roller, and means to drive the platen roller step by step to feed the papers; a member automatically moved by operation of the machine, and an actuator element for said member, said member being arranged to engage a portion of said pressing means when actuated by said element and during its movement to first move said pressing means away from the platen roller to release said papers from feeding relation to the platen roller and then release said pressing means to permit the latter to again press said papers into feeding relation to said platen, and said element being arranged to then actuate said means to drive the platen

roller to feed the papers prior to the termination of the movement of said element.

2. In a paper feeding mechanism for printing business machines having a rotatable platen roller around which a plurality of strips of paper are passed, paper pressing means to press the paper strips into feeding relation to the platen roller, said pressing means being movably mounted for movement toward and away from the platen roller, yieldable means to urge the pressure means toward the platen roller, means to drive the platen roller step by step to feed the paper strips, paper take-up means including means to tension a portion of at least one of said paper strips which has passed around and beyond the platen roller, and means to drive said tensioning means; a member automatically moved by operation of the machine and engaging a portion of said pressing means to move said pressing means away from the platen roller to release said paper strip from feeding relation to the platen roller to permit said tensioning means to move said one of the paper strips relative to the platen roller.

3. A paper feeding mechanism for printing business machines having means supporting a supply roll of multiple-wound paper strips, a rotatable platen roller around which a plurality of strips of paper from said supply roll are passed, paper pressing means to press the paper strips into feeding relation to the platen roller, said pressing means being movably mounted for movement toward and away from the platen roller, yieldable means to urge the pressure means toward the platen roller, spacing means to drive the platen roller step by step to feed the paper strips, a paper take-up roll to wind up the portion of at least one of said paper strips which has passed around and beyond the platen roller, means to drive said take-up roll, said driving means including a yielding power-storing means urging said take-up roll to advance to a greater extent peripherally than said platen, and a member automatically moved by operation of the machine and engaging a portion of said pressing means to move said pressing means away from the platen roller to release said paper strips from feeding relation to the platen roller and permit

5

10

20

25

30

35

40

45

said yielding means to rotate said take-up roll to advance said one of the paper strips relative to the platen roller and tension the portion thereof between said platen roller and said supply roll.

4. A paper feeding mechanism for printing business machines, comprising means to support a supply roll of multiple-wound paper strips, a platen roller around which a plurality of strips from said supply roll are passed, the strip outermost on said supply roll being innermost on said platen roller, a pressure roller, movable means to support said pressure roller, means acting on said supporting means to press said pressure roller against said paper strips to press the latter into feeding relation to said platen roller, means to rotate said platen roller step by step in one direction to feed said paper strips, means to hinder reverse rotation of said platen roller, a take-up roll to wind up a portion of the strip which has passed innermost around and beyond said platen, an elastic belt driven by said platen roller and driving said take-up roll, and tending to advance the periphery of said take-up roll to a greater extent than the periphery of said platen roller advances whereby unequal tensions are produced in portions of said belt by paper feeding and winding rotations of said platen roller and take-up roll, and a member moved automatically by operation of the machine and acting on said pressure roller supporting means to retract said pressure roller from said platen, to release said paper strips from feeding relation to said platen roller to permit said belt to advance the take-up roll and pull the strip innermost around the platen roller relative to another of said strips to equalize the lengths of the strips between the supply roll and platen roller.
